UNITED STATES PATENT OFFICE

CARL GILMORE, OF OAKLAND, CALIFORNIA

BEACH CHAIR

Application filed September 18, 1928. Serial No. 306,647.

My invention relates to improvements in beach chairs; and one of the objects of the present invention is to provide a chair that may be disposed upon lawn, seashore, camp ground, or elsewhere, and which will provide rest and comfort to the occupant or occupants;

A further object of the invention is to provide a chair that may be readily folded into a compact bundle for purposes of transportation, storage, or the like, and as readily unfolded when it is desired to use the same;

A still further object of the invention is the provision of a chair adaptable for use in combination with the umbrella commonly in use along seashore resorts for protection against the sun, wind or dust;

A still further object is the provision of a chair of this character, having two seats and backs upon and against which two persons may sit or recline with great comfort.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a perspective view looking towards the rear of the chair as set up for occupancy by one or two persons;

Figure 2 is a rear elevation of the chair partly folded, the fabric forming the seat and back-rest having been omitted in order to present a clearer view of the frame work;

Figure 3 is a detailed elevation of upper central portions of the device;

Figure 4 is a side elevation, partly in section, of upper and lower portions of the central or tubular support of the chair;

Figure 5 is another view in elevation of a portion of the central support;

Figure 6 is a side view, with an intermediate portion broken away, of one of the cross-bars;

Figure 7 is a cross sectional view on line 7'—7' of Fig. 6;

Figure 8 is a detailed view of the lower end portion of one of the chair supports;

Figure 9 is a view in elevation of one of the clamp bands, detached from the upper end portion of the tubular support;

Figure 10 is a sectional view on line 10'—10' of Fig. 3;

Figure 11 is a cross section on line 11'—11' 60 of Fig. 2; and

Figure 12 is an enlarged view, partly sectional, of upper portions of the frame-work looking in the direction indicated by the arrow "a".

Referring now more strictly to the details of the drawings, throughout the several views of which like reference characters designate like parts:

The numerals 1 and 2 designate the central 70 and the two side supports, respectively, of the present invention, while the numeral 3 designates the two rear supports, and 4 and 5 represent the diagonal braces thereof.

The central support 1 is substantially in 75 the form of a tube, which is preferably constructed of sheet metal, and has one end of a cylindrical pin 6 projecting fixedly a distance upward into its lower end. The pin 6, which is preferably formed of wood, 80 should by preference fit sufficiently tight in the tube 1 to be frictionally bound therein against movement relative thereto by the normal use and handling of the chair.

It is however further secured in the tube 85 by means of a screw 7 employed primarily for securing one end of a clamping spring 8 against the side of said tube, and which projects through registering openings provided in said tube and spring. Certain of 90 the functions of the central or tubular support 1, together with the pin 6, as well as the spring 8, will hereinafter be fully described.

9 and 10 designate a pair of opposed, concave-convex, clamping bands, which are 95 preferably formed of strips of sheet metal and terminate at their ends into outwardly extending lips 11, 12, provided with suitable openings through which project double-headed rivets 13. The lips 11 are spaced 100

such distances from the lips 12, to permit inserting therebetween of the inner ends of lower cross bars 14, 14, which are provided with suitable openings in said ends, through which said rivets project, and whereby said ends are pivotally supported for movement between said lips.

The clamping bands 9, 10, encircle the pin 6 adjacent its lower or free end, and are fixedly held thereon by means of a screw 15, which projects through an opening in the band 9 and extends into said pin a proper distance.

The outer ends of the cross bars 14, 14, are pivotally secured to the side supports 2, at points thereon preferably a short distance upwardly from their lower ends, by means of pivot pins 16, 16, which project through both said side supports and said cross bars.

17, 18, designate a pair of co-operable, concavo-convex, clamping bands having their ends formed into outwardly projecting spaced lips 19, 20, between which are pivotally secured the inner ends of upper cross bars 21 by means of rivets 22. The clamping bands 17, 18, which are fixedly disposed to encircle the tubular standard 1 adjacent its upper end, are similar to the bands 9, 19, heretofore described, with the exception however that in place of the securing screw 15 extending through the band 9, there is provided a headed stud 23, which extends through an opening 23' in the band 17, and which has a flattened base 24 disposed between said band 17 and the standard 1, whereby said stud is held substantially in fixed relation to said band.

The upper cross bars 21, which are preferably equal in length to the lower cross bars 14, have their outer ends pivotally secured to the upper ends of the side supports 2, by means of rivets 21'.

The tubular support 1, side supports 2, and the upper and lower cross bars 21 and 14, are disposed substantially in the same plane, with the axes of their securing rivets extending substantially at right angles through said plane, when the chair is extended into its open position as best illustrated in Fig. 1 of the drawings.

To the side supports 2, at suitable distances thereon downwardly from their upper ends, are pivotally secured the upper ends of the two rear supports 3, 3. The latter operatively swingable in the plane of the side support to which it is attached.

To the rear supports 3, 3, adjacent their lower ends, are pivotally secured the lower ends of the diagonal braces 4, 5, whereby the latter may be operatively moved, relatively to the side supports, substantially in the plane of the latter, when the device is operated from an open to a folded position, or vice versa.

65 The brace 4, viewing it from the rear when

the chair is set up or extended, has its upper end bent upwardly and to the left to better conform with the rear side of the tubular support 1, to which it is removably secured by means of the stud 23, the head of the latter is for which purpose projected through a key-hole-like opening 25 formed in the upper end of said brace 4. The upper portion of the opening 25 is made sufficiently large relative to the head of the stud 23 to permit it to pass freely therethrough, but the lower or laterally restricted portion of said opening, which restricted portion is adapted to movably accommodate the shank of the stud, is however too small or narrow to permit the head of the stud passing through it, therefore, when the chair has been opened or extended, as best shown in Fig. 1, and it is desired to maintain it in such position, the upper end of the brace 4 is manipulated so that the head of the stud 23 will pass outwardly through the upper portion of the opening 25. The brace is then moved upwardly relative to said stud until the shank of the latter moves into the restricted portion of the opening as far as it will normally go, thereby releasably locking said upper end of the brace against the side of the tubular support 1. Obviously, by reversing the action just described, the brace 4 may be released from the tubular support 1 when it is desired to fold the chair.

The brace 4, which has its lower end pivotally connected to the lower end portion of its co-operable rear support 3, restricts any transverse movement of the latter relative to the chair, when its upper end is locked against the upper end of the tubular support 1.

The diagonal brace 5, which is somewhat shorter than the brace 4, has its lower end pivotally connected to the lower end portion of its co-operating rear support 3, and its upper end pivotally connected to the upper end of the brace 4 at a point thereon a distance below the opening 25, said brace thus being adapted to restrict transverse movement of said rear support 3, when the chair is extended as for occupancy.

The relative arrangement of the rear supports 3, 3, and the braces 4, 5, and the connections between them, as well as the connections between the former and the side supports, are such that when the upper end of the brace 4 is released from the tubular support 1, the said rear supports and their braces may readily be folded in substantially a common plane into contiguous relative parallelism.

26, 26, designate the two laterally separated elements forming the seat and the back-rest members of my improved chair, which members may be formed of such woven material as canvas, ducking, or the like, and are provided at both their upper and lower ends with loops or hems 27, 27, 27, 27, through which

extend the upper and lower cross bars 14, 14 and 21, 21, and by which cross bars said members are supported. It will be found unnecessary to remove the members forming the 5 seats and back-rests from their respective cross bars when folding the chair, as they are made sufficiently full or long to permit them to fold and to otherwise adjust themselves to the movement of the frame-work of 10 the chair when it is folded.

The present improved beach chair is intended as a convenient and useful device for use in parks, playgrounds, camps, lawns or the seashore, particularly at the latter, and 15 on, or in which, one or two persons may sit or recline for rest and the like. And while the device is complete and useful for the purposes above mentioned, as well as for other purposes, without any additional attachments 20 for providing shade or shelter, it is nevertheless particularly useful in combination with the conventional umbrella commonly found along the beaches, for providing additional shade, shelter from wind or 25 dust, as well as for protection against rain. It is for this reason that the central support 1 is made in the form a hollow tube, into which the handle or shaft of an umbrella may be readily thrust for holding the latter over 30 or above the chair. The pin 6 at the bottom of the tube 1 acting as a stop adapted to receive the end of the umbrella handle for limiting its movement in the tube in a downwardly direction.

35 When the chair is set up on loose soil or sand, the lower ends of the supports may be permitted to sink a distance thereinto without interfering in the least with the usefulness of the chair. In some instances I have 40 found it desirable to permit the seat portions of the members 26 to rest on the sand, or soil, and in other instances, depending on circumstances, I have found it desirable to even excavate the sand to some extent below 45 the seat portion of device to permit the seat to be disposed below the surface of the surrounding sand.

To fold the chair, it is simply necessary to remove the upper end of the diagonal brace 50 4 from the stud 23, thence swing the rear supports forward against the side supports, and thence the side supports, together with the rear supports and their braces, upwardly relative to and against the center or tubular support. When an umbrella is used in 55 conjunction with the chair, it is preferably removed before folding the latter.

While the principal portion of the frame-work, the center support excepted, is formed 60 of suitable commercial angle iron, a cross sectional view of the preferred type of which is shown in Fig. 7, other suitable material may be substituted therefor.

65 The spring clamp 8, which is preferably formed of spring steel, and which has one

end fixedly secured to the lower end portion of the tube 1, by means of the screw 7, whereby its other end is held to spring-press against the tube, is intended to be used for holding such personal articles as papers, handkerchiefs, gloves, reticules, or one or several of other relatively small articles which the occupants may wish to dispose of temporarily, and which may be readily secured by the clamp by pinching the same between the 75 latter and the tube.

I claim:

1. In a beach chair of the character described, a central support and a pair of side supports disposed in lateral spaced relation, 80 rear supports having their upper ends pivotally secured to upper end portions of said side supports, and diagonal braces connecting the lower end portions of said rear supports and said central support together.

2. A foldable chair comprising a pair of front side supports, a single central front support between said side supports, upper and lower cross bars between each side support and said central support pivoted at their inner ends to said central support and at their outer ends to said side supports, respectively, whereby the latter are swingable substantially into parallelism with and against said central support, a seat and back rest member carried by said cross bars between said central support and each side support, and rear supports pivotally connected to said front supports.

3. A foldable chair comprising a pair of front side supports, a single central front support between said side supports, upper and lower cross bars between each side support and said central support pivoted at their inner ends to said central support and at their outer ends to said side supports, respectively, whereby the latter are swingable substantially into parallelism with and against said central support, a seat and back rest member carried by said cross bars between 105 said central support and each side support, a rear support pivoted at its upper end to each side support for forward and backward swinging movement with respect thereto, brace bars pivotally connected with said rear supports, and means for detachably connecting said brace bars with said central support.

4. A foldable chair comprising a pair of front side supports, a single central front support between said side supports, upper and lower cross bars between each side support and said central support pivoted at their inner ends to said central support and at their outer ends to said side supports, respectively, whereby the latter are swingable substantially into parallelism with and against said central support, a seat and back rest member carried by said cross bars between said central support and each side support, a rear support pivoted at its upper end to each side 120 125 130

support for forward and backward swinging movement with respect thereto, brace bars pivotally connected with said rear supports and with one another, and means for detachably connecting one of said brace bars with said central support.

5. A foldable chair comprising a pair of front side supports, a single central front support between said side supports, seat carrying cross bars connecting said side and central supports for swinging movement between positions substantially parallel closely adjacent and relatively widely spaced with respect to one another, a rear support pivoted at its upper end to each side support for forward and backward swinging movement with respect thereto, and a brace bar pivotally connected at its lower end to each rear side support, and means whereby the upper ends of said brace bars are detachably connected with said central support.

10. A foldable chair comprising a pair of front side supports, a single central front support between said side supports, seat carrying cross bars connecting said side and central supports for swinging movement between positions substantially parallel closely adjacent and relatively widely spaced with respect to one another, a rear support pivoted at its upper end to each side support for forward and backward swinging movement with respect thereto, and a brace bar pivotally connected at its lower end to each rear side support, a pivoted connection between said brace bars, one of said brace bars having a slot therein, and a pin carried by said central support with which said slotted brace bar is adapted for detachable connection by means of the slot therein.

15. A foldable chair comprising a pair of front side supports, a single central front support between said side supports seat carrying cross bars connecting said side and central supports for swinging movement between positions substantially parallel closely adjacent and relatively widely spaced with respect to one another, a rear support pivoted at its upper end to each side support for forward and backward swinging movement with respect thereto, a brace bar pivotally connected at its lower end to each rear side support, a pivotal connection between said brace bars, and a quick detachable pin and slot connection between one of said brace bars and said central support.

20. A foldable chair as set forth in claim 2 wherein the upper end portion of the central front support is tubular and open at its upper end for the reception thereinto of the handle of an umbrella.

In testimony of the foregoing being my own, I have hereunto affixed my signature this 29th day of August, 1928.
